UNITED STATES PATENT OFFICE.

MAXIMILIAN CHARLES SCHWEINERT, OF WEST HOBOKEN, NEW JERSEY, AND HENRY P. KRAFT, OF NEW YORK, N. Y.

SOCKET MEMBER FOR WATER-BAGS.

1,046,501.

Specification of Letters Patent. Patented Dec. 10, 1912.

Application filed July 13, 1908. Serial No. 443,216.

To all whom it may concern:

Be it known that we, MAXIMILIAN CHARLES SCHWEINERT, residing in West Hoboken, in the county of Hudson and State of New Jersey, and HENRY P. KRAFT, residing in the borough of Brooklyn, county of Kings, city and State of New York, both citizens of the United States, have jointly invented certain new and useful Improvements in Socket Members for Water-Bags, of which the following is a specification.

This invention relates to water bags or similar articles of the type in which the bag is molded in one piece as distinguished from those bags which are formed of a number of pieces of rubber cloth vulcanized together.

In the manufacture of molded water bags a suitable mold is dipped in a rubber solution a sufficient number of times to build up a wall of proper thickness. After the last coat is dried the mold with its rubber covering is placed in the vulcanizing chamber so that the bag vulcanizes upon the mold. In this type of bag in order that the mold 25 may be removed after vulcanization it is necessary to provide the bag with a comparatively large neck. This prevents the use of the usual type of socket member which is of a diameter only slightly exceeding that of 30 the stopper, and requires a socket member of sufficient proportions to practically fill the neck.

According to our invention we provide an improved socket member of this type which 35 is of cheap and simple construction, which permits a proper finish of the exterior parts, and which prevents the retention of any water within the bag when the latter is emptied.

According to the accompanying drawings wherein we have illustrated one form of our invention,—Figure 1 is a sectional view of a water bag provided with our improved socket member, the section being taken along the major diameter of the socket member. Fig. 2 is a similar view taken along the minor diameter of such member. Fig. 3 is a plan view of the socket member. Fig. 4 is a view showing the two parts of which the 50 member is constructed detached. Fig. 5 is a sectional view of a modified form.

Referring to the drawings, let A indicate a water bag of any suitable shape and made

by the molding process hereinbefore referred to, such water bag having an enlarged neck 55 B and a short funnel portion C.

D is the usual stopper which is adapted to screw into the socket member E. The socket member E is formed in two sections, the top section F being formed of a flat plate G, the middle portion of which is drawn downwardly in a suitable press to form a tubular extension H, the side walls of which are screw-threaded and the bottom of which is provided with an inturned flange I. The top plate is also formed with a peripheral flange J which is designed to engage the lower section K. The latter section is formed of a plate of metal drawn to cup-shape and provided with internally bent side walls L. At its middle the bottom of the cup K is apertured at M to register with the opening within the flange I of the upper member F, around which opening the parts are connected. This may be done by means of interlocking flanges on the upper and lower members, such as are shown for instance in Figs. 1 and 2, wherein the bottom wall of the lower member L is formed with a flange O which is turned over the flange I of the upper member. The flanges may be soldered in this position if desired, although this will not ordinarily be necessary. Or the construction shown in Fig. 5 may be adopted wherein the two parts are soldered together. By any of the constructions just described a seat for the stopper is formed at the bottom of the socket member. In connecting the parts the lower member K is inserted within the flange J of the upper member F and the flange is then rolled down so as to unite the parts as shown in Figs. 1 and 2. The outwardly turned upper edge of the lower member L permits the flange J to make a secure joint between the parts by simply turning it inwardly as shown.

The shape of the socket member may be varied considerably. Usually it will have an oval form so as to conform as far as possible to the flat shape of the bag. It may be attached to the bag in any desired way, as for instance by winding the neck of the bag with wire such as N, the wire being covered by a suitable tape or binding P.

When the two sections of the socket member are united an extremely strong and light

construction is attained. The screw-threaded portion H being united at its top and its bottom to the upper and lower walls of the socket member, is made stiff and rigid so that no distortion is liable to take place.

An important feature of the invention is that the lower wall of the stopper is closed so that the entire bag may be emptied without retaining any water within it. Preferably the connection between the tubular member H and the lower wall is such that no leakage into the interior of the socket member will be possible. The construction prevents any possible distortion of the wall 10 L by the pressure of the uniting wire N or by the shocks and strains of use. A tight joint between the bag and socket member is thus always assured.

Another important feature of the invention is that it is possible to finish the socket member by nickel plating it or by other means without an excessive cost. It is practically necessary that the wall L shall be free from plating in order that a tight joint may 20 be secured between the bag and the socket member. On the other hand, it is desirable to nickel the top plate G and the tubular member H. By the present construction the top section F can be nickelated separately 25 while the lower section is left without finish. If the wall L and the top plate G were formed in one piece, it would be necessary to nickel the entire structure and to subsequently remove the plating from the wall L. 30 This would involve a relatively large and unnecessary expense.

While we have shown in detail but one form of our invention it will be understood that we do not wish to be limited thereto as 40 various modifications may be made therein without departing from the invention.

What we claim is:-

1. A socket member for water bags or the like, comprising a hollow body, having top 45 and bottom walls, and an interior screw-threaded wall passing through said body and connected leak-tight to said top and bottom walls.

2. A socket member for water bags or the like, comprising a hollow body formed of a 50 plurality of sections, said body having a screw-threaded opening therethrough.

3. A socket member for water bags or the like, comprising a hollow body formed of a 55 plurality of sections, said body having top and bottom walls and an interior screw-threaded wall passing through said body and connected to said top and bottom walls with a leak-tight joint.

4. A socket member for water bags or the like, comprising two sections, one of which 60 is cup-shaped and the other of which is formed with a tubular screw-threaded member, said sections being united, said cup-shaped member having an opening there-

through and said screw-threaded member being connected to said cup-shaped member around said opening.

5. A socket member for water bags or the like, comprising two sections, one of which 70 is cup-shaped and the other of which is formed with a tubular screw-threaded member, one of said sections having concave side walls, said sections being united, said cup-shaped member having an opening there- 75 through and said screw-threaded member being connected to said cup-shaped member around said opening.

6. A socket member for water bags or the like, having an upper wall, side walls 80 connected to said upper wall, a lower wall connecting said side walls, and a tubular screw-threaded member having its upper end connected to said upper wall, and its lower end connected to said lower wall, said 85 tubular member being smaller than the body of said socket member, and said upper and lower walls being formed with apertures coincident with said tubular member, and said socket member being formed in two 90 parts, one of which is cup-shaped, and the other of which is formed with said tubular extenson and a flange forming one of said upper and lower walls, said flange being connected to the free edge of said cup- 95 shaped member.

7. A socket member for water bags or the like, having an upper wall, side walls connected to said upper wall, a lower wall connecting said side walls, and a tubular 100 screw-threaded member having its upper end connected to said upper wall, and its lower end connected to said lower wall, said tubular member being smaller than the body of said socket member, and said upper and 105 lower walls being formed with apertures coincident with said tubular member, and said socket member being formed in two parts, the lower of which is cup-shaped and includes said bottom wall and said side 110 walls, and the upper of which includes said top wall and said tubular member.

8. A socket member for water bags or the like, having an upper wall, side walls connected to said upper wall, a lower wall 115 connecting said side walls, and a tubular screw-threaded member having its upper end connected to said upper wall, and its lower end connected to said lower wall, said tubular member being smaller than the body 120 of said socket member, and said upper and lower walls being formed with apertures coincident with said tubular member, and said socket member being formed in two parts, the lower of which is cup-shaped and includes said bottom wall and said side 125 walls, and the upper of which includes said top walls and said tubular member, said side walls being concave and said top wall being flanged over said side walls. 13

9. A socket member for water bags or the like, comprising two sections, the lower of which is cup-shaped and has concave walls, and the upper of which is formed 5 with a tubular screw-threaded member, said upper and lower members being united at their edges, and said lower section having an aperture opposite said tubular member and being connected thereto around said aperture, said upper section being provided 10 with a metal plating and said lower member being in unplated condition.

10. A socket member for water bags or the like, comprising a hollow sheet metal 15 member having upper and lower walls, and a tubular screw-threaded member connected to both said walls, said screw-threaded member having a flange and one of said walls having a flange, said flanges being interlocked.

11. A socket member for water bags or the like, comprising a hollow sheet metal member having an integral tubular screw-threaded member having an inturned flange 20 at its end, and a bottom plate having a

flange turned over the flange of the tubular screw-threaded member.

12. A socket member for water bags or the like having an upper wall, side walls connected to said upper wall, a lower wall 30 connected to said side walls, and a tubular screw-threaded member located between said upper and lower walls, said tubular member being smaller than the body of the socket member and being spaced apart from said 35 side walls, said upper and lower walls being formed with apertures coincident with said tubular member, and said socket member being formed in two parts, said tubular extension and said side walls being each 40 formed integral with a wall of the socket member.

In witness whereof, we have hereunto signed our names in the presence of two subscribing witnesses.
